CIGARETTE PACKAGE CONTAINER
Richard E. Watkins, 1917 Westway, Garland, Tex.
Filed Oct. 27, 1960, Ser. No. 65,509
4 Claims. (Cl. 206—41.2)

This invention relates generally to cigarette package containers or cases, and is particularly directed to a combination container which may serve the dual purpose of holding a package of cigarettes and which may act to receive ashes from such cigarettes.

The primary object of this invention is to provide an inexpensive construction for cigarette package containers which may be utilized to receive ashes as well as function to receive a complete package of cigarettes.

The more specific object of this invention is to provide a combination ash tray and cigarette package holding container with an operating pull tab construction which will function to open the container, partially remove the package of cigarettes, and simultaneously open the ash receptacle portion of the container.

With the foregoing and other objects in view, the invention resides in the following specification and appended claims, certain embodiments of details of construction of which are illustrated in the accompanying drawings in which:

FIGURE 1 is a perspective view of the container comprising the invention;

FIGURE 2 is a perspective view of the container of FIGURE 1 illustrating the container in opened condition, a package of cigarettes partially removed from the container, and the ash receiving opening of the container;

FIGURE 3 is a sectioned view in side elevation taken along the lines 3—3 of FIGURE 1 illustrating the cover of the container in the open position with the dotted lines showing the cigarette package in partially removed position; and

FIGURE 4 is a sectioned view in side elevation of a modified form of the container with an integral pull tab construction.

Referring now more particularly to the drawings, the container 10 includes a generally rectangular series of panels of material, preferably formed from one blank sheet, there being side panels 11 and 12 and front and back panels 13 and 14. The lower end of the container is closed by an end panel 15 while the access end of the container is closed by a hinged cover member 16.

Front panel 13 is cut-away at 17 to provide an opening 18, said opening being generally positioned toward the lower end 15 of the container. It will be noted that the opening 18 is placed or located on the front panel 13 while the hinged connection between the cover 16 and the container proper is located along one edge 19 of the back panel 14.

Affixed to the interior of the container along the inner surface of panel 13 between the ash receiving 18 and the access opening of the container by any suitable means such as an adhesive, is a combination closure flap and operating pull tab 20 of flexible material, the functions of which will be hereinafter described. The combination unit 20 includes a flap portion 21 which, when the container is closed, is positioned by the cigarette package held by the container in such a manner as to close the opening 18 in the panel 13 of the container 10. The elongated tab 22 of the combination unit 20 extends from an integral relationship with the flap 21 along the inner surface of the back wall 14 of the container 10 upwardly within the cover 16 of the container and downwardly beyond the lower edge 23 of the cover 16 to a position along the outer surface of front panel 13 of container 10, so that the tab may be grasped by the fingers of a person utilizing the invention.

2

The operation of the invention should now be readily apparent to one skilled in the art. With the container 10 holding a package of cigarettes within its confines, as indicated in FIGURES 1 and 2 and the person utilizing the invention desiring to smoke a cigarette, it is merely necessary to pull on tab 22 in the general direction of the longitudinal axis of the container whereby the cover 16 for the container will be opened, the contents, namely a package of cigarettes, will be partially removed by engagement of the tab and flap area of the combination unit 20 with the lower end of the cigarette package, and the flap 21 will be pulled downwardly about a transverse hinged connection 24 with the panel 13 so that the portion of the container 10 between the rear edge of the cigarette package and the container end 15 may be utilized as an ash receptacle. The hinged connection 24 is determined along the edge of the adhesive connecting between the container and the combination unit. It is thus obvious that the pull tab unit has three simultaneously operative functions, namely, opening the cover 16 of the container 10, partially removing the cigarettes in packaged form and depressing the flap 21 to make opening 18 lead directly to the ash tray portion now formed by part of the container.

The combination unit 20 is enlarged, flanged and folded to conform to the interior of container 10 as is illustrated at 29 in FIGURE 2 whereby the container panels are strengthened in the area of the access opening.

In the modified form of the invention illustrated in FIGURE 4 cognizance is taken of the fact that it may be desirable to have the flap 25 formed as an integral portion of a front panel 26 and that the pull tab 27 be directly connected thereto. Thus it will be noted that the upper front cover 26 is folded back upon itself at upper edge 28 to extend inwardly of the container 10 to terminate in the integral flap and tab unit. Otherwise the construction of FIGURE 4 is quite similar to that of FIGURES 1, 2 and 3 and the operation thereof is identical.

It should be readily apparent to one skilled in the art that the container 10 may be formed of any suitable material and that such container may be utilized with any generally standard package of cigarettes either of normal or king size with regard to length. Likewise the configuration of the container might be modified for the purpose of accommodating specially contoured or sized cigarette packages. Such modifications as well as detail modifications of the flap and pull tab structure in connection with the combination utility container are considered well within the purview of this inventor who intends only to be limited to a reasonable interpretation of the appended claims.

I claim:

1. A cigarette package container comprising a hollow shell of substantially rectangular configuration, having front, back and side panels, a lower end panel and an upper access opening, a closure for the access opening of said shell hinged along the access opening edge of the back panel of the shell, said front panel having an ash receiving opening positioned generally toward the lower end panel of the shell, a combination unit including a closure flap for said ash receiving opening and a pull tab affixed to the interior of said shell in such a manner that the flap portion of said combination unit is hinged adjacent the edge of the ash receiving opening toward the access opening of the container, and so that the pull tab of said unit is generally positioned in a free manner along the inner surface of the lower and back panels of the container and extends longitudinally of the container to the access opening, is reversed upon itself and is then extended to a position normally adjacent the front wall of the container when the container closure is in the closed position.

2. The invention according to claim 1 wherein the combination unit is an integral extension of the front panel of the container.

3. A cigarette package container comprising a hollow shell of substantially rectangular configuration, being formed of a plurality of integral panels, one of which is a lower end panel, and having an upper access opening for the reception of a cigarette package, one of said integral panels including an ash receiving opening, cover means to normally close said access opening, and a combination unit including closure means for said ash receiving opening and an elongated actuating means extending therefrom along the inner surface of said container to said access opening and beneath said cover means to the exterior of said container, said combination unit being secured to a contact point on the interior of said shell above the lower end panel whereby operation of

4
said actuating means from the exterior of said container simultaneously causes said closure means to flex inwardly from said contact point to uncover said ash receiving opening, said actuating means to move against said cover means to cause dislodgment thereof, and the tensioning of said actuating means, whereby said actuating means moves toward the access opening of said container to partially remove the contents thereof.

5
10 4. The invention according to claim 3 wherein the combination unit is an integral extension of one of said plural integral panels.
